(57) **CLAIM**

The ornamental design for a position adjusting member for cutting tool, as shown and described.

DESCRIPTION

FIG. 1 is a front view of a position adjusting member for cutting tool showing my new design;
FIG. 2 is a rear view thereof;
FIG. 3 is a right side view thereof;
FIG. 4 is a left side view thereof;
FIG. 5 is a top view thereof;
FIG. 6 is a bottom view thereof;
FIG. 7 is a first perspective view thereof;
FIG. 8 is a second perspective view thereof;
FIG. 9 is a cross sectional view taken along line 9-9 in FIG. 5;
FIG. 10 is a cross sectional view taken along line 10-10 in FIG. 5;
FIG. 11 shows a position adjusting member for cutting tool in an environment of use thereof; and,
FIG. 12 shows a position adjusting member for cutting tool in an environment of use thereof.
The broken lines shown in views represent portions of the positioning member for cutting tool that form no part of the claimed design.
